DOOR FASTENER

Roland J. Olander, Chicago, Ill., assignor to W. H. Miner, Inc., Chicago, Ill., a corporation of Delaware

Application January 22, 1941, Serial No. 375,424

3 Claims. (Cl. 292—218)

This invention relates to improvements in door fasteners for hinged doors.

One object of the invention is to provide a door fastener, especially adapted for swinging or hinged doors of refrigerator railway cars, wherein means is provided for bracing the doors against weaving action when locked by the fastener.

Another object of the invention is to provide a fastener for hinged doors of refrigerator cars comprising a rotary locking bar mounted on the door, cooperating keepers above and below the door with which the keeper engaging means on the bar is engageable to lock the door in closed position, and cooperating interengaging locking means on the bar and top and bottom keepers, respectively, to rigidify the door structure with respect to the car body when the door is fastened in closed position, thereby positively holding the door against weaving.

A more specific object of the invention is to provide a fastener as set forth in the preceding paragraph, wherein the cooperating locking means on the operating bar and keepers comprises a pair of locking lugs on the bar at the top and bottom ends thereof, engageable within horizontally arranged seats formed in the keepers.

Other objects of the invention will more clearly appear from the description and claims herein-after following.

In the drawings forming a part of this specification Figure 1 is an elevational view of a portion of the side wall of a refrigerator car provided with a pair of hinged doors, illustrating my improvements in connection therewith. Figure 2 is an enlarged elevational view of the structure shown in Figure 1 at the lower ends of adjacent portions of the doors. Figure 3 is a horizontal sectional view, corresponding substantially to the line 3—3 of Figure 2. Figure 4 is a vertical sectional view, corresponding substantially to the line 4—4 of Figure 2.

In said drawings 10 indicates a portion of the side wall of a refrigerator car provided with a door opening 11 closed by the usual pair of hinged doors 12 and 13. The doors 12 and 13 are supported along their vertical outer edges by the usual hinge members 14—14—14 which are of well-known design. As is understood by those skilled in this art the hinged doors 12 and 13 are provided with beveled meeting edges, the edge of the door 12, which is the door last closed, overlapping the adjacent edge of the door 13. It is also the usual practice to bevel the cooper-

ating engaging edges of the doors and the walls of the door opening and provide all engaging edge portions with compressible insulating material.

My improved door fastener comprises broadly 5 top and bottom keepers A and B secured to the car wall; a vertically disposed rotary operating bar C mounted on one of a pair of hinged doors; top and bottom keeper engaging crank members D—D on the bar; locking lugs E—E at the top and bottom ends of the bar; seats F—F provided in the keepers with which the lugs E—E are engageable; and an operating handle lever G for rotating the bar.

The keepers A and B are of similar design, except as hereinafter pointed out. As shown in 15 Figure 3, each keeper has an inwardly directed cam slot 15 of well-known design within which the corresponding keeper engaging crank portion of the operating bar is engageable to force the 20 door tightly closed or pry the same partly open. The top and bottom keepers A and B are secured to the wall of the car, respectively, above and below the door opening 11, in any suitable manner, preferably by bolts extending through the 25 bodies of the keepers and the car wall 10. Each keeper is provided with an outstanding portion 16 which is upstanding on the keeper B. As shown in Figures 3 and 4, the portion 16 of the keeper B is provided with a horizontal slot 17 defined by vertically spaced, horizontally disposed top and bottom walls 18 and 19, the top wall 18 being in the form of a ledge overhanging the bottom wall 19. The inner corners of the outer or front end portions of the top and bottom 30 walls are beveled off, as indicated at 20—20, to provide a flaring mouth portion or entrance opening to the slot. The structure just described forms the seat F with which the corresponding lug member E of the operating bar engages. The keeper A at the top of the door opening is also provided with an outstanding portion 16 presenting a seat F similar to the seat F hereinbefore described, and having a slot defined by vertically spaced walls, the slot being indicated by 17, and 35 the walls by 18 and 19. This structure of the keeper A is the same as that of the lower keeper B but the arrangement thereof is reversed, that is, the outstanding portion 16 is depending and the walls 18 and 19 are respectively bottom and top. The cam slot 15 of the keeper A, which is engaged by the corresponding crank arm of the operating bar, differs from the slot 15 of the keeper B in that it opens downwardly instead of upwardly. The slot 17 of the seat F of the keeper 40 A is also provided with a flaring mouth defined 45

by beveled edges 20-20 on the walls 18 and 19.

The bottom keeper B differs from the keeper A in that it is provided with a horizontally extending arm portion 21 on which a latch finger 22 is pivoted. The latch finger 22 is of well-known design and is engageable over the lower inner corner of the door 13 to latch the same in closed position, the corner of this door being provided with the usual protective wear plate 23, as shown.

The rotary operating bar C is preferably of rectangular transverse cross section and has end members 24-24 secured to the top and bottom end portions thereof. Each end member has a keeper engaging crank member D formed at the outer extremity thereof. The bar C is rotatably supported by bearing brackets 25-25 secured to the door 12 adjacent the top and bottom end portions of the latter. The end members 24-24, the crank members D-D, and the supporting brackets 25-25 are all well-known in this art and therefore no further detailed description thereof is required, however, it might be pointed out that the end members are forked at their inner ends to embrace the corresponding end portions of the bar C to which they are riveted, and that the portions of the end members intermediate the forked portions and the crank member D thereof are of cylindrical shape and journaled in the bearing openings of the brackets 25-25.

Each crank member D comprises a horizontally disposed, radially extending crank arm 26 provided with a crank pin portion 27 at the outer end thereof engageable within the slot 15 of the corresponding keeper. The crank end of each end member 24 is provided with a radial lug E which is disposed in substantially horizontal alignment with the crank arm 26 but circumferentially spaced therefrom so as to form an obtuse angle with the same and so arranged that the lug E will be fully seated in the slot 17 of the seat member F when the keeper engaging crank pin portion of the corresponding crank member D is seated in the slot 15 of the keeper in door locking position. The leading edge of each lug E is beveled off at the top and bottom, as indicated at 27-27, to facilitate entrance of the lug within the mouth of the slot 17 of the seat of the corresponding keeper. The lugs E-E snugly fit the slots 17-17 of the keepers so that with the bar in locking position it is positively held against vertical displacement with respect to the keepers A and B and the wall of the car, thereby rigidly supporting the door against weaving.

The bar C is operated by the usual hand lever G which may be locked against displacement by a latch 28 ordinarily employed for this purpose to maintain the door in fastened and closed position.

As is well known to those skilled in this art to open or close the door the bar C is rotated by the handle lever G to cam the door outwardly or inwardly through the action of the crank members D-D within the slots 15-15 of the keepers. As the bar is rotated to open the door, the lugs E-E are disengaged from the

seats F-F while the crank pins of the crank arms 26-26 are leaving the slots 15-15 of the keepers, thereby freeing the door 12 to be swung open. In rotating the bar C to fasten the door by engagement of the crank members with the keepers, the lugs E-E are swung into the slots 17-17 of the seats F-F and engaged between the walls 18 and 19 of said slots to lock the bar against vertical displacement.

I have herein shown and described what I now consider the preferred manner of carrying out my invention, but the same is merely illustrative and I contemplate all changes and modifications that come within the scope of the claims appended hereto.

I claim:

1. In a fastener for a hinged door of a container, the combination with a fixed keeper on said container, said keeper having a horizontally disposed slot defined by horizontally disposed, vertically spaced, top and bottom walls, said keeper also having a second slot defined by spaced vertically disposed walls; of a vertically disposed rotary operating bar on said door; a radial lug on said bar engageable within the first named slot of said keeper between said horizontally disposed walls of said slot to lock the bar to said keeper against vertical displacement; and a crank member on said bar engageable within the second named slot of said keeper between the vertical walls of said slot to force the door closed and fasten the same in closed position.

2. In a fastener for a hinged door of a container, the combination with fixed keepers on said container above and below the door, each of said keepers having a horizontally disposed slot defined by horizontally disposed top and bottom walls, each of said keepers having a second slot defined by horizontally extending, vertically disposed side walls; of a vertically disposed operating bar on said door; radially disposed horizontal lugs at the top and bottom ends of said bar, each of said lugs being engageable within the first named slot of the corresponding keeper between said horizontal walls of said slot; and top and bottom crank members on said bar engageable respectively with said keepers, each crank member engaging within the second named slot of the corresponding keeper between the walls thereof to force said door closed and fasten the same in closed position.

3. In a fastener for a hinged door of a container, the combination with a fixed keeper on said container, said keeper having a slot defined by vertically spaced, horizontally disposed walls, and a second slot defined by laterally spaced, vertical side walls, said first named slot having a flaring mouth; of a vertically disposed rotary operating bar on said door having a radially disposed horizontal lug engageable in said first named slot, said lug being beveled to facilitate entrance thereof into the mouth of said slot; and a crank member on said bar engageable within said second named slot to force the door to closed position and fasten the same in said closed position.

ROLAND J. OLANDER.
